UNITED STATES PATENT OFFICE.

JOHN BULANDA, OF PULLMAN, ILLINOIS, ASSIGNOR OF ONE-HALF TO FRANCISZEK BULANDA, OF PULLMAN, ILLINOIS.

WINDOW-LOCK.

1,340,876.

Specification of Letters Patent. Patented May 25, 1920.

Application filed November 13, 1919. Serial No. 337,697.

To all whom it may concern:

Be it known that I, JOHN BULANDA, a citizen of Poland, residing at Pullman, in the county of Cook and State of Illinois, 5 have invented certain new and useful Improvements in Window-Locks, of which the following is a specification.

The primary object of the invention is the provision of a sash lock adapted for 10 normally holding a window sash at the desired vertical adjustment readily releasable from a point inwardly of the window frame to permit the shifting of the sash in either direction.

15 A further object of the invention is to provide a window sash retainer including simultaneously operable bolt and ratchet means whereby the sash is adapted for ratcheting movement in either direction 20 until secured by the bolt when the ratchet automatically assumes a wedged retaining position against the sash.

A still further object of the invention is to provide a sash lock that is easy to install upon a window possessing great 25 strength in holding the sash adjusted and providing the ratchet retaining means for maintaining the sash in adjusted position when the mechanism is released and at 30 which time the sash may be forcibly shifted either upwardly or downwardly.

With these general objects in view, the invention consists of the novel combination and arrangement of parts hereinafter more 35 fully described in connection with the accompanying drawings and in which like reference characters designate corresponding parts throughout the several views.

In the drawings,

40 Figure 1 is a front elevation of a portion of a window having my invention installed thereon.

Fig. 2 is a side elevation of the window frame,

45 Fig. 3 is a sectional view through the window casing showing the racks upon the sashes,

50 Fig. 4 is a vertical sectional view through a portion of a window casing and sash illustrating the invention in its locked position,

Fig. 5 is a view of the inner face of the window casing showing the bolt and latch mechanism,

55 Fig. 6 is a horizontal sectional view upon the line VI—VI of Fig. 4,

Fig. 7 is a view similar to Fig. 4 with the device released,

Fig. 8 is a vertical sectional view taken upon line VIII—VIII of Fig. 4,

Fig. 9 is a horizontal sectional view 60 taken upon line IX—IX of Fig. 4, and

Fig. 10 is a perspective view of the mechanism of the device which is adapted to be carried by the window casing.

Referring more in detail to the drawings, 65 my invention is designed for holding as well as locking vertically shiftable sashes 10 and 11 at points of adjustment in the window casing 12. Corresponding sides 13 and 14 of the sashes 10 and 11 respectively 70 are provided with suitable racks 15 having spaced teeth 16 adapted for ratchet engagement by the pivoted latch 17 herein-after described while sockets 18 in the racks 15 are adapted for the seating recep- 75 tion of spring pressed bolts 19 when the sashes are in their closed positions.

A U-shaped frame 20 carried by a plate 21 is secured through the window frame 22 for holding the lock and latch mecha- 80 nism of identical construction for each of the sashes 13 and 14. The frames 20 are positioned adjacent each other through the window frame member 22 as illustrated in Fig. 2 of the drawings, a wooden panel 23 85 being preferably secured overlying the plate 21.

An elongated yoke 24 is pivoted at one end to a bracket 25 within the frame 20 with its opposite end normally held outwardly by a leaf spring 26 as well as by a spring pressed catch 27 pivoted in the frame 20 with the free end of the yoke 24 normally resting upon a shoulder 28 90 of the catch.

The latch 17 is pivoted through the yoke 24 by a pin 29 while leaf springs 30 carried by the yoke normally bear upon the arcuate base 31 of the latch 17 for normally holding the latch 17 with the tines 100 of its forked free end 32 engaging the rack teeth 16. When the yoke 24 is locked in its normal position by the catch 27, the adjacent window sash may be shifted in one direction permitting the latch 17 to 105 ratchet over the teeth 16 to prevent the opposite movement of the sash by wedging the latch 17 between the yoke 24 and the toothed rack of the sash.

A curved lever 33 pivoted at 34 to the 110

plate 21 has a finger 35 at one end thereof normally engaging the upper end 36 of the catch 27 which end is shiftably positioned in a slot 37 of said plate 21. A push rod 38 5 shiftable through the window sash 11 has its inner end positioned in a groove 39 in the adjacent side of the lever 33 while a push button 40 is provided upon the outer end of the rod 38. Inward pressure upon 10 the button 40 rocks the lever 33 releasing the catch 27 from the yoke 24 whereby the forcible shifting of the adjacent sash swings the latch 17 to its opposite extremity of movement which is permitted by the outward swinging of the yoke 24 against the 15 action of the spring 26.

The bolt 19 already referred to is mounted in a housing 41 upon the plate 21 with a spring 42 normally projecting said bolt so 20 as to enter the keeper socket 18 of the adjacent sash rack when the sash is in its closed position as best illustrated in Figs. 4 and 9 of the drawings. A rocker shaft 43 journaled beneath the plate 21 has an arm 44 articulated with the bolt 19 for retracting the same against the action of the spring 42 when the shaft 43 is rocked in one direction by means of a curved arm 45 projecting within the path of movement of the 25 lever 33. Upon forcing the rod 38 inwardly by the push button 40, the arm 45 is engaged by the lever 33 and the shaft 43 rocked causing the arm 44 to retract the bolt 19 simultaneously with the release of 30 the catch 27 from the yoke 24 as heretofore described. The panel 23 has a slot 46 corresponding to the slot 47 in the plate 21 and through which slots the latch 17 is shiftably positioned while an opening 48 in the 35 panel 23 accommodates the bolt housing 41. The complete operation of the invention will be understood from this detail description thereof, it being seen that the complete mechanism is provided for either or both of 40 the sashes 10 and 11 as herein set forth and is so positioned as to lock the sash 10 closed when elevated and the sash 11 closed when lowered, the bolts 19 engaging the keeper sockets 18 for this purpose while the latch 45 17 for each sash retains the same closed after the manner of a wedge by reason of the inability of the yokes 24 to shift pivotally when the bolts 19 are in their projected positions.

50 When the bolt 19 is retracted by inwardly pressing the push button 40 thereof, the yoke 24 is resiliently positioned inwardly by its spring 26 with the latch 17 engaging the adjacent rack 15 of the corresponding 55 window sash for ratcheting thereover during either upward or downward movement of the sash, the engagement between the teeth and latch being maintained by the

springs 30. When the sash is elevated with the bolt retracted, the latch 17 is adapted to hold the sash in its adjusted position by means of the spring 26 outwardly positioning the yoke 24 until the sash is shifted with considerable force to pivotally move the yoke 24 as illustrated in Fig. 7 of the drawings. Upon releasing the rod 38, the bolt 19 is automatically projected by its spring 42 for engaging the rack teeth 16 at any adjustment of the sash although a more firm locking of the sash is effected when the 75 sash is closed by the seating of the bolt 19 in the keeper socket 18 of the sash rack.

While the form of the invention herein set forth is believed to be the preferable embodiment thereof, it will be understood 80 that minor changes may be made therein without departing from the spirit and scope of the invention.

What I claim as new is:—

1. A sash lock comprising a rack upon 85 the sash, a pivoted yoke upon the casing, a swinging latch upon the yoke adapted for ratcheting engagement with the rack, normal positioning means for the yoke, a retaining catch for the yoke when the latch 90 is in its operative position, a curved lever upon the casing adapted for releasing said catch, a shiftable rod normally engaging said lever extending exteriorly of the casing, said rack having keeper sockets therein, a spring pressed bolt carried by the casing adapted for engaging the teeth of the rack and for seating in said sockets when the sash is closed, and an operative arm connected to said bolt extending within the 100 path of travel of said lever whereby the bolt is retracted during the inward movement of the latch operating rod.

2. A sash lock comprising a rack upon 105 the sash, a swinging yoke upon the casing, a latch for the rack carried by said yoke, means for holding the yoke in one position with the latch operatively engaging the rack, and normally operable means for releasing the yoke holding means to permit 110 the sash and rack to slide free of the latch.

3. A sash lock comprising a rack upon 115 the sash, a swinging yoke upon the casing, a latch for the rack carried by said yoke, means for holding the yoke in one position with the latch operatively engaging the rack, normally operable means for releasing the yoke holding means to permit 120 the sash and rack to slide free of the latch, and a tensioned sliding bolt adapted to engage the rack to lock the sash in adjusted positions, said bolt being released from the rack by said manually operable means.

In testimony whereof I affix my signature.

JOHN BULANDA.
